(57) CLAIM

The ornamental design for a decanter, as shown and described.

DESCRIPTION

FIG. 1 is a top, front, right side perspective view;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a cross-section view taken along line 8-8 of FIG. 5; and,

FIG. 9 is a top, front, right side perspective view with environmental matter shown thereof.

In the drawings, the broken lines are for the purpose of illustrating environment only, and form no part of the claimed design.

1 Claim, 9 Drawing Sheets
